CLAIM

The ornamental design for a wheel-shaped input device for control panel as shown and described.

DESCRIPTION

FIG. 1 is a front, right-side, bottom perspective view of a wheel-shaped input device for control panel, showing the new design;

FIG. 2 is a front elevational view thereof; and,

FIG. 3 is a bottom plan view thereof; the top plan view, the left-side elevational view, and the right-side elevational view, none of which are provided, being identical thereto. The broken lines depict portions of the wheel-shaped input device for control panel that form no part of the claimed design.
